UNITED STATES PATENT OFFICE.

SIDNEY JENNINGS, OF STANGATE, COUNTY OF SURREY, ENGLAND.

DEVICE OR BUSH FOR FIXING THE TRUNNIONS OF BASINS USED IN TIP-UP LAVATORIES, &c.

SPECIFICATION forming part of Letters Patent No. 410,795, dated September 10, 1889.

Application filed January 4, 1889. Serial No. 295,384. (No model.) Patented in England May 7, 1888, No. 6,791.

To all whom it may concern:

Be it known that I, SIDNEY JENNINGS, sanitary engineer, a subject of the Queen of Great Britain, residing at Stangate, in the 5 county of Surrey, England, have invented certain Improvements in Trunnion-Bushes, (for which I have previously obtained Letters Patent in Great Britain, dated May 7, 1888, No. 6,791,) of which the following is a full, clear, 10 and exact description.

This invention relates to improvements in trunnion-bushes for supporting tip-up-lavatory-basins. Such bushes have heretofore been fixed in inverted U-shaped lugs or recesses 15 formed on opposite sides of the basin, the trunnions resting on semicircular bearings provided in the frame-work or wash-table, such semicircular bearings allowing the basin to be readily lifted out when required.

20 In practice it is found that through careless tilting when employing the basin the trunnions are displaced and the lugs, which are formed of porcelain homogeneous with the basin, are brought into contact with the metal 25 bearings and thereby damaged. To prevent this, I have devised a new form of bush, which is illustrated in the accompanying drawings, of which—

Figure 1 is a side elevation of a portion of 30 the basin, and Fig. 2 a vertical section through line x x of Fig. 1.

A is the bush, which is fixed, as usual, in the recess provided for it between the earthenware lugs B, which are integral with the basin.

35 The trunnion A' projects, as usual, from the

center of the bush, and on the outer edge of the latter is formed a flange or rim A². This flange only extends around about three-fourths of the circumference of the bush, an opening being left sufficiently wide for the bearing C 40 to pass through, which passage can only be effected by keeping the basin in a horizontal position when raising or lowering it. If the trunnion is displaced when merely tilting the basin, the flange or rim A² comes in contact 45 with the convex or under side of the bearing C and prevents the total displacement of the trunnion, besides protecting the lugs B from injury.

Having thus particularly described my invention, what I claim as new, and desire to secure by Letters Patent, is—

1. In a basin-support, the combination, with a basin provided with a trunnion and with a partially-surrounding flange having an opening smaller than its internal diameter, of a trunnion-bearing having a horizontal dimension a little less than the width of said opening, substantially as set forth. 55

2. The herein-described trunnion-bush A, 60 provided with a trunnion A' and a surrounding flange A², of more than a half-circle, having an opening on its under side, substantially as set forth.

SIDNEY JENNINGS.
